[57] CLAIM

The ornamental design for a dispenser head, as shown and described.

DESCRIPTION

FIG. 1 is a perspective view of a dispenser head showing my new design;

FIG. 2 is a front elevational view thereof, the rear being a mirror image;

FIG. 3 is a top view thereof;

FIG. 4 is a left side elevational view thereof; and,

FIG. 5 is a right side elevational view thereof.

The surfaces or portions of the article not shown in the drawing or described in the specification form no part of the claimed design.
